Fig. 9

FIG. 1 is a perspective view of a drapery rod embodying the present invention;

FIG. 2 is a front elevational view;

FIG. 3 is a bottom plan view of the drapery rod shown in FIGS. 1 and 2;

FIG. 4 is an enlarged elevational view of the end opposite that shown in FIG. 1;

FIG. 5 is a perspective view of a drapery rod embodying a modified form of the present invention;

FIG. 6 is a front elevational view of the drapery rod shown in FIG. 5;

FIG. 7 is a bottom plan view of the drapery rod shown in FIGS. 5 and 6;

FIG. 8 is an enlarged elevational view of the end of the drapery rod opposite that shown in FIG. 5;

FIG. 9 is a perspective view of a drapery rod embodying a further modified form of the present invention;

FIG. 10 is a front elevational view of the drapery rod shown in FIG. 9;

FIG. 11 is a bottom plan view of the drapery rod shown in FIGS. 9 and 10; and

FIG. 12 is an enlarged elevational view of the drapery rod opposite that shown in FIG. 9.

I claim:

The ornamental design for a drapery rod, substantially as shown and described.
